CLAIM

The ornamental design for a escalator handrail entry housing, as shown and described.

DESCRIPTION

FIG. 1 is a perspective view of an escalator handrail entry housing as seen from the front right side showing our new design. The broken line showing of the entry way and handrail is for illustrative purposes only and form no part of the claimed design;

FIG. 2 is an enlarged perspective view of the entry housing of FIG. 1 without the broken line showing it; FIG. 3 is a perspective view of the front left sides thereof;

FIG. 4 is a top view thereof; and,

FIG. 5 is a perspective view showing the front and underside thereof.

The broken lines shown in the drawings illustrate the environment upon which the article is mounted and are not a part of the claimed design.

The undisclosed rear is open and unornamented.
